DIE FORMING MACHINE,
APPLICATION FILED AUG. 31, 1921.

Patented Dec. 5, 1922.

4 SHEETS—SHEET 4.

UNITED STATES PATENT OFFICE.

MILLO H. DUNBAR, OF CANTON, OHIO.

DIE-FORMING MACHINE.

Application filed August 31, 1921. Serial No. 497,214.

To all whom it may concern:

Be it known that I, MILLO H. DUNBAR, a citizen of the United States, residing at Canton, in the county of Stark and State of Ohio, have invented a new and useful Die-Forming Machine, of which the following is a specification.

This invention relates to die forming machines and has for its objects to provide a device of this character especially adapted for forming battery terminals and similar articles, which may be cast of lead or other metal which may be easily poured.

With these objects in view the invention consists in the construction and arrangement of parts, hereinafter described and illustrated in the accompanying drawings, it being understood that various changes in the form and details of construction may be made within the scope of the appended claims.

A preferred embodiment of the invention thus set forth in general terms is illustrated in the accompanying drawings, in which—

Figure 1 is a front elevation of a machine embodying the invention, parts being broken away for the purpose of illustration;

Fig. 2, an end elevation of the same;

Fig. 3, a plan view thereof;

Fig. 4, an enlarged, longitudinal, sectional view through the dies;

Fig. 5, a transverse, sectional view through one of the water jackets; and

Fig. 6, a vertical, sectional view through a battery terminal such as is formed in the device.

Similar numerals of reference indicate corresponding parts throughout the several views.

The device includes the bed plate 1 which is longitudinally slotted as at 2 and provided with the depending flanges 3 upon opposite sides of said slot. The bed plate is supported as by the standards 4 which are preferably connected together by the longitudinal brace bars 5, a transverse web 6 being supported upon said bars intermediate their extremities.

The form of die illustrated is designed for forming a battery terminal such as is shown in cross section in Fig. 6 which includes the stem 7 provided with the annular flange 8, the threaded portion 9 and the tapered extremity 10, a flange 11 extending upon opposite sides of the lower end portion of the

stem in the usual manner for connecting the battery plates.

The terminal illustrated is provided with a central brass tube 12, internally screw threaded, and the dies which are shown in the accompanying drawings are designed to form this terminal with the brass tube therein.

The die includes the spool 13 provided with a central bore 14 outwardly flared at its upper end as shown at 15 to form the conical or tapered end 10 of the terminal. An annular flange 16 is provided around the lower end portion of the spool 13 and rests upon the top of the bed plate, being held fixedly thereon by means of the screws 17 which are passed upwardly through the disk 18 located against the bottom edges of the flanges 3.

A rod or post 19 is fixed at its lower end to the disk 18 and extends upwardly through the bore 14 of the spool 13, having the reduced shouldered pin 20 at its upper extremity arranged to receive the brass tube 12, the open end thereof engaging the shoulder 21 of said pin to position the tube properly within the die.

A pair of sliding dies 22 are mounted for horizontal movement upon the bed plate and are arranged to engage each other and the spool 13, as best shown in Fig. 4. Each of these sliding dies is provided upon its inner face with a half round cut-out portion as at 23 to receive the spool 13, the threaded cut-out portions 24 being formed in the inner surfaces of said dies and communicating with the cut-out portions 23.

The half round cut-out portions 25 provided with the enlarged, half round recesses 26, are formed in said dies above the threaded portions to form the body portion of the stem 7 and the flange or rib 8, the cut-out threaded portions 24 being provided to form the threads 9 upon the finished battery terminal as shown in Fig. 6.

The plates 27, 28 and 29 are mounted upon the upper surfaces of the dies 22, the plates 27 being provided with the cut-out portions 30 to form the flanges 11 upon the battery terminal, the plates 28 and 29 being provided with the cut-out portions 31 and 32 respectively, forming a pouring spout into which the molten metal is poured.

These plates are loosely mounted upon the upper surfaces of the dies 22, the posts 33 be-

ing carried upon the dies 22 and extending upwardly through suitable apertures in said plates, the upper extremities of said posts being threaded and provided with the nuts 34, coil springs 35 being located around the posts between the nuts and the upper surfaces of the plates 29, thus holding the plates normally in the position shown in Fig. 4, but allowing for movement of the 10 plates which is often necessary in separating the dies 22 after a terminal has been cast or molded therein.

Each of the sliding dies 22 is preferably provided with a water jacket 36, for the 15 purpose of cooling the die, these jackets being preferably attached to the dies by means of the screws 37 which are also passed through the angular sliding brackets 38, these brackets being slidably mounted upon 20 the bed plate, bolts 39 being carried by the brackets and depending through the annular slot 2 in the bed plate, plates 40 being carried upon the lower extremities of the bolts, these plates being spaced slightly 25 beneath the flanges 3 in order to allow the brackets 38 to be moved horizontally upon the bed plate.

The water jackets 36 are provided with the inlet and outlet apertures 41 and 42 respectively, each inlet aperture being connected to a suitable source of water supply as by the flexible hose 43, a hose 44 being connected to each outlet aperture for the purpose of carrying the heated water away 30 from the water jackets. The circulation of cold water may thus be constantly passed through each water jacket during the operation of the machine.

A bell crank lever 45 is pivoted as at 46 40 between the flanges 3 near each end of the bed plate, the upper end thereof being connected as by the link 47 with the adjacent sliding bracket 38. The lower leg 48 of each bell crank is provided with a plurality 45 of spaced apertures 49 for selective engagement of the pivot 50 of the adjacent connecting rod 51, said connecting rods being provided with means for longitudinal adjustment such as the turnbuckles 52.

50 A pair of spaced upright posts 53 are mounted upon the web 6 and slidably mounted thereon is the pedal 54, provided with the spaced bearings 55 and 56 which are slidably mounted upon the posts 53. A 55 bar 57 is connected to the upper ends of the posts 53 to act as a bumper or stop for the pedal, the ends thereof extending beyond the posts on either side and carrying the upper ends of the contraction springs 58, the lower ends of which are connected to 60 the lugs 60 upon the pedal for the purpose of normally holding the pedal in the initial position, as shown in Fig. 1.

In operating the device, the parts being 65 in the initial position as shown in the draw-

ings, the pedal is depressed and through the connecting bars 51, bell cranks 45 and links 47, the sliding brackets 38 are moved oppositely away from the spool 23. A brass tube 12 is then placed upon the pin 20 in 70 the position shown in Fig. 4, and the pedal released, allowing the parts to assume the initial position, the dies being closed, as best shown in Fig. 4.

The molten metal is then poured from a 75 ladle or the like into the pouring spout 32 of the dies, and as soon as the metal has cooled, which in the case of lead is almost instantaneous, especially with the use of the water jackets as shown, the pedal is depressed opening the dies when the finished article may be easily removed from the pin 20.

The top portion of each movable die 22 being formed of a series of vertically movable plates, it will be seen that the dies may be easily and quickly moved outwardly out of engagement with the finished article, the plates 27, 28 and 29 being allowed to move vertically to disengage the dies from the 90 finished product.

Although the dies illustrated are designed for the purpose of casting a particular form of battery terminal, it will be evident, of course, that other dies may be provided in 95 the machine for casting articles of different shapes, without departing from the invention.

I claim:—

1. A device of the character described, including a bed plate, a spool fixed upon the bed plate, a pair of oppositely movable dies slidably mounted upon the bed plate, arranged to enclose the spool, bell cranks upon opposite ends of the bed plate, a link connecting each bell crank to the adjacent die, a pedal, and connecting rods connecting the bell cranks to the pedal. 100

2. A device of the character described, including a pair of oppositely movable dies and a plurality of plates mounted upon the upper surface of each die and arranged for independent movement perpendicular to the normal plane of the dies. 110

3. A device of the character described, including a pair of oppositely movable dies and a plurality of plates mounted upon the upper surface of each die, and flexible means for holding said plates in engagement with each other and with the dies. 115

4. A device of the character described, including a pair of oppositely movable dies and a plurality of plates mounted upon the upper surface of each die, posts carried by said dies and extending through said plates and spring means upon the posts engaging the upper surfaces of the upper plates. 125

5. A device of the character described, including a bed plate, a pair of oppositely movable dies mounted upon the bed plate, 130

bell cranks upon opposite ends of the bed plate, a link connecting each bell crank to the adjacent die, a pedal, and connecting rods connecting the bell cranks to the pedal.

5 6. A device of the character described, including a bed plate, standards supporting the bed plate, a web supported at the lower ends of the standards, a pair of oppositely movable dies mounted upon the bed plate, a

10 bell crank mounted at each end of the bed

plate, a link connecting each bell crank to the adjacent die, a pair of upright posts upon said web, a pedal slidably mounted upon said posts, connecting rods connecting said bell cranks with the pedal and springs 15 for normally holding the pedal in the raised position.

In testimony that I claim the above, I have hereunto subscribed my name.

MILO H. DUNBAR.
